FIG. 1

FIG. 2

FIG. 3

FIG. 1 is a perspective view of a handle for paint rollers and brushes showing my new design;

FIG. 2 is a view in elevation as seen from the opposite side of FIG. 1; and

FIG. 3 is a bottom view thereof.

The broken line disclosure of a fragmentary rod is for illustrative purposes only and forms no part of the claimed design.

I claim:

The ornamental design for a handle for paint rollers and brushes, substantially as shown and described.
